UNITED STATES PATENT OFFICE.

CHRISTIAN C. BOHN, OF NEW YORK, N. Y.

JOINT-COVER OR KICK-PLATE.

SPECIFICATION forming part of Letters Patent No. 739,282, dated September 22, 1903.

Application filed February 21, 1903. Serial No. 144,478. (No model.)

To all whom it may concern:

Be it known that I, CHRISTIAN C. BOHN, a citizen of the United States, residing in the city of New York, in the county of New York and State of New York, have invented certain new and useful Improvements in Joint-Covers or Kick-Plates, of which the following is a specification.

It is old in the art of installing conduits for electric circuits to place the conducting-wire in wooden moldings fastened to the walls or ceilings. For the purpose of fire protection it is prohibited to run these moldings through partitions or walls, and it is compulsory to insulate each individual wire by means of fireproof tubing, such as porcelain tubes, &c., and have these tubes protect the conducting-wire when carried through walls, &c. In using the two insulating means, wooden moldings and fireproof tubing, it is necessary to provide means for covering and protecting the place of abutment of the same in order to prevent damage to the conduits; to protect the conducting-wire, and avoid the accumulation of dust, dirt, &c.

The object of the present invention is to provide simple and efficient means for accomplishing this purpose, and the nature of this invention is fully disclosed and described in the following specification and illustrated in the accompanying drawings.

Figure 1 of the drawings is a front view of the structure. Fig. 2 is a similar view, partially cut away. Fig. 3 is a horizontal cross-section in the plane of the top of the fireproof tubing. Fig. 4 is a vertical cross-section of the device, showing one of the tubes in side view; and Fig. 5 is a perspective side view of the joint-cover proper, commonly called a "kick-plate."

1, in Figs. 2 and 4, is the regular wooden molding, such as extensively used in wiring houses, &c.

2 is the usual wooden strip for covering the wire after the same has been put in place. The molding is ordinarily nailed or screwed to the walls, and when the conducting-wire is to be carried through a wall, ceiling, &c., the molding is brought quite close to the

corner formed by the wall and floor or wall and ceiling. Tubes 4, made of suitable fire-proof insulating material—such as porcelain, vitreous material, fiber, &c.—are used to carry the wire 3 through these floors, partitions, &c. For the purpose of giving room for the tubes 4 the middle portion 10 of the molding 1 is suitably cut away, so that the conducting-wire 3 may be carried directly from the grooves of the molding 1 into the hollow of the tubes 4. A joint-cover or kick-plate, Fig. 5, of metal, fiber, vitreous or other suitable material, is then placed about the recess in the molding 1, containing the tubing 4, so that its front 5 covers said recess and its sides 6 surround the side portions of the molding 1. Suitable flanges or other means 7, provided with screw-holes 8, are used to fasten this joint-cover or kick-plate 5 to one of the walls or partitions by means of screws 9 or nails, so that it may rest with one of its open sides against the other of the walls forming the corner with the first one.

This device so constructed is a very efficient protection for the end of the molding as well as for the tubing containing the conducting-wire. It is easily applied and removed. Different dimensions of the joint-cover or kick-plate of course may be used as well as different material to construct the same according to different requirements without departing from the intended scope of the present invention.

What is claimed as new and useful, and desired to be protected by Letters Patent, is—

1. The combination with a molding comprising a strip and partitions integral therewith forming longitudinal outer channels, of individual fireproof conduits abutting with the channels of the molding, a kick-plate for covering the outer sides of the molding and the fireproof conduits at the abutment of the channels and the conduits, and means for covering the channels and abutting with the upper ends of the kick-plate.

2. The combination with a molding having outer longitudinal channels, of conduits abutting with the channels, electrical conductors passing through the conduits and the chan-

nels, a kick-plate forming an integral structure surrounding the outer sides of the molding and the abutting ends of the conduits and the channels, means for covering the channels and means for securing the kick-plate to the wall.

In testimony whereof I have hereunto set

my hand, in the presence of two subscribing witnesses, this 19th day of February, 1903.

CHRISTIAN C. BOHN.
